United States Patent Office

Des. 187,885
Patented May 10, 1960

187,885

FORK OR SIMILAR ARTICLE

Jens H. Quistgaard, Copenhagen, Denmark, assignor to
Dansk Designs Inc., Great Neck, N.Y.

Original application May 19, 1958, Serial No. 50,958,
now Design Patent No. 186,167, dated September 22,
1959. Divided and this application March 25, 1959,
Serial No. 55,176

Term of patent 14 years

(Cl. D54—12)

FIG. 1

FIG. 2

FIG. 3

FIG. 4

FIG. 5

Fig. 1 is a front plan view of a fork, showing my new design;

Fig. 2 is a reverse plan view thereof;

Fig. 3 is a side elevation thereof;

Fig. 4 is an enlarged section taken on line 4—4 of Fig. 1; and

Fig. 5 is an enlarged section taken on line 5—5 of Fig. 1.

This application is a division of original application D. 50,958, filed May 19, 1958, for A Set of Flatware. This title has been changed to A Knife or Similar Article and a patent thereon was issued under No. D. 186,167, dated September 22, 1959.

I claim:

The ornamental design for a fork or similar article, substantially as shown and described.
